FISHING LURE

Harold Drew Owen, 2605 Woodruff Road,
Edmond, Okla. 73034

Filed Aug. 13, 1973, Ser. No. 387,775

Term of patent 14 years

Int. Cl. D22—05

U.S. Cl. D22—27

FIG. 1 is a side view of the fishing lure. The opposite side is the same as that shown.

FIG. 2 is a top view of the fishing lure. The bottom view of the lure is the same as the top view.

FIG. 3 is a front elevational view of the lure.

FIG. 4 is a rear elevational view of the lure.

FIG. 5 is a sectional view of the lure as viewed with the covering of the lure removed on one side of the lure.

I claim:

The ornamental design for fishing lure, substantially as shown and described.
